UNITED STATES PATENT OFFICE.

CHESTER ARTHUR BARR, OF PORTLAND, OREGON, ASSIGNEE, BY DIRECT AND MESNE ASSIGNMENTS, TO THE DUFUR VENTILATOR COMPANY, A CORPORATION OF OREGON.

WINDOW-VENTILATOR.

1,204,391.

Specification of Letters Patent. Patented Nov. 14, 1916.

Application filed May 28, 1915. Serial No. 31,059.

To all whom it may concern:

Be it known that I, CHESTER A. BARR, a citizen of the United States of America, residing at Portland, in the county of Multnomah and State of Oregon, have invented new and useful Improvements in Window-Ventilators, of which the following is a specification.

This invention relates to improvements in 10 ventilators for use in the windows of buildings, cars, and other structures and in all places where ventilation is required, the object of the invention being to provide an improved device of this character which is 15 cheap and simple in construction, which may be readily attached to a window or other support, and which while admitting the free passage of air, prevents rain, snow and the like from entering through the 20 ventilator and also prevents the entrance of flies and other insects.

The invention consists in the features of construction, combination, and arrangement of devices, hereinafter fully described and 25 claimed.

In the accompanying drawings: Figure 1 is an elevation of a ventilator constructed and arranged in accordance with my invention, a portion of the body being removed 30 and disclosing the segmental shutter and also disclosing a portion of the screen. Fig. 2 is an elevation showing the outer side of the ventilator and with a portion of the weather hood removed, to disclose a portion 35 of the weather shutter. Fig. 3 is a vertical sectional view showing one end of the ventilator. Fig. 4 is a vertical sectional view taken on the plane indicated by the line 1—1 of Fig. 1.

40 The sash rail or other base H is provided with an oblong rectangular opening K, for the passage of air therethrough. A screen i of wire cloth or other suitable material is secured to the inner side of the sash rail, over said opening. The body A of the 45 ventilator is semi-tubular and may be made of sheet metal or any other suitable material. The body has closed ends as at a' and is also provided with outstanding side flanges 50 a. Said flanges are provided with openings for the reception of screws wherewith the ventilator is secured to the inner side of the sash rail and arranged over the opening K as shown. The body of the ventilator is 55 provided with air inlet openings b in its

upper side and is also provided in its upper side with a vertical slot c which is spaced mid-way between the ends of the body.

The ventilating shutter C, which is segmental in form is arranged in the body a 60 and bears and fits against the inner side of the wall thereof. A knob b is secured to this shutter by a screw f and operates in the slot c. By grasping this knob, the shutter C may be moved upwardly to close 65 the opening b and thereby cut off the inlet of air or may be lowered to uncover said openings.

A storm hood B is arranged on the outer side of the sash rail H over the opening K 70 and has an upwardly extending flange g which is secured to the sash rail by screws as shown. A storm shutter E is arranged in the hood, is hingedly mounted at its upper edge as at j, and is connected by a rod D 75 to the shutter C, said rod being connected to the shutter C as at e and having its outer end threaded, passed loosely through and opening in the storm shutter E, and provided with nuts h which are secured thereon 80 and which are arranged on opposite sides of said shutter E as shown.

The storm shutter is thus connected to the ventilating shutter and when the latter is lowered, to uncover the opening b, the shutter E is also moved to open position so that air can enter the room through the hood B, the opening K, the screen i, the chamber formed by the body of the ventilator A, and the opening b. 85

It will be understood that the hood B effectually excludes rain and snow. When the shutter C is moved to closed position, the storm shutter E is also moved to closed position as will be understood. 90

Having thus described my invention, I claim:

1. In combination with a base having an opening, a ventilating device on the inner side of the base, and comprising a substantially semi-tubular body, covering said opening, closed at the ends, and having openings in its wall, a shutter mounted for movement on the wall to cover and uncover said openings, a hinged outer shutter mounted on the outer side of the body and a connection between said shutters to cause the outer shutter to be operated with and by the first named shutter. 100

2. In combination with a base having an 110

opening, a ventilating device on the inner side of the base, and comprising a substantially semi-tubular body, covering said opening, closed at the ends, and having 5 openings in its wall, a shutter mounted for movement on the wall to cover and uncover said openings, a hinged outer shutter mounted on the outer side of the body and a connection between said shutters to cause

the outer shutter to be operated with and 10 by the first-named shutter, and an outer hood on the outer side of the base covering said opening, and to which the upper side of the outer shutter is hingedly connected.

CHESTER ARTHUR BARR.

Witnesses:
